Attorney

UNITED STATES PATENT OFFICE.

HARLEY C. MOORE, OF PRESCOTT, MICHIGAN.

SUPPLEMENTAL OIL RESERVOIR.

Application filed July 18, 1922. Serial No. 575,896.

To all whom it may concern:

Be it known that HARLEY C. MOORE, a citizen of the United States of America, residing at Prescott, in the county of Ogemaw 5 and State of Michigan, has invented new and useful Improvements in Supplemental Oil Reservoirs, of which the following is a specification.

The object of the invention is to provide 10 simple and efficient means whereby an extra or supplemental supply of lubricating oil may readily be carried by a vehicle of the motor-driven type in such a position and relation to the parts of the mechanism as to be 15 maintained at a proper temperature even in cold weather to adapt it to flow readily to the point of application to the mechanism as for example to the crank case, and whereby the transfer of the contents thereof to the 20 crank case or other part of the mechanism requiring lubrication may be effected with facility and without loss of time to the operator and moreover without the risk of wastage; and with these objects in view the 25 invention consists in a construction and combination of parts of which a preferred embodiment is shown in the accompanying drawings, wherein:—

Figure 1 is a view in perspective of a supplemental oil reservoir and supporting means arranged in operative relation with the motor of a vehicle of the type indicated.

Figure 2 is a side view of the same.

Figure 3 is a detail plan view of the bracket by which the oil can or receptacle is supported.

The device consists essentially of a preferably rectangular oil can or receptacle 10 and a bracket 11, shown in detail in Figure 40 3, forming a seat for the can or receptacle and which is adapted to be supported upon the motor cylinders as indicated at 12 simply by engaging the requisite number of the cylinder head bolts 13 with suitable openings 14 45 formed in forwardly directed arms 15 constituting elements of the bracket. In the construction illustrated the bracket consists of longitudinal bars 16 connected near their ends by transverse members 17 which 50 are extended to form the arms 15, said transverse members being provided with front and rear upstanding arms 18 and 19 of which the latter which are yieldable transversely

with relation to the space bounded by the elements of the seat are provided with terminal catches 20 adapted to be displaced to permit the seating of the can and to spring over the upper edge thereof to prevent accidental displacement by reason of the jarring or vibration of the vehicle when in motion. The 60 terminals of the longitudinal bars 16 are upturned to form ears 21 for bearing contact with the ends of the can or receptacle to prevent endwise displacement.

The bracket constituting a substantial seat 65 for the can or receptacle may thus be attached to and remain in fixed relation with the motor cylinders and may be provided in a convenient position at one end with a faucet 22 adapted, if desired, to be locked 70 or secured against surreptitious opening, and when it is desired to supply oil to the crank casing indicated at 23 a conveyor tube 24 may be arranged to connect the faucet with the filling opening 25 of said 75 crank case, the conveyor tube preferably being reduced in diameter toward its upper end so as to snugly fit the outlet of the faucet and thereby minimize the risk of loss of the oil in its transfer from the reservoir through 80 the crank case. To guide the operator in supplying oil to the crank case a gauge glass 26 may be arranged in communication therewith at any convenient point.

Having described the invention, what is 85 claimed as new and useful is:—

A reservoir support adapted to be applied to an engine casing comprising a bracket having angularly disposed end portions, one portion adapted to be secured to 90 the engine casing, the extremity of the other portion being resilient and having a catch, and an arm passing transversely through the portion of the bracket which is secured to the engine casing and disposed parallel with 95 the resilient portion of the bracket, said arm adapted to extend along the side of the engine casing and in contact therewith and provided at its lower end with a brace portion which is inclined upwardly and attached to the portion of the bracket which is secured to the engine casing at a point intermediate the ends thereof.

In testimony whereof he affixes his signature.

HARLEY C. MOORE.
